UNITED STATES PATENT OFFICE.

HENRY MUELLER, DECEASED, LATE OF DECATUR, BY ORA B. MUELLER AND ADOLPH MUELLER, EXECUTORS, AND ANTON C. SCHUERMANN, OF DECATUR, ILLINOIS, AS SIGNORS TO H. MUELLER MFG. CO., OF DECATUR, ILLINOIS, A CORPORATION OF ILLINOIS.

SELF-CLOSING COCK OR FAUCET.

1,046,399.

Specification of Letters Patent. Patented Dec. 3, 1912.

Application filed November 19, 1910. Serial No. 593,201.

To all whom it may concern:

Be it known that HENRY MUELLER, deceased, late a citizen of the United States, and resident of Decatur, county of Macon, and State of Illinois, and ANTON C. SCHUERMANN, a citizen of the United States, and resident of Decatur, county of Macon, and State of Illinois, did during the lifetime of the said HENRY MUELLER jointly invent certain new and useful Improvements in Self-Closing Cocks or Faucets, of which the following is a specification.

This invention comprises a self-closing cock of the type in which the valve is opened by pushing the same, and the closure automatically effected upon release of the same. It will be apparent upon an understanding of the invention, that it is applicable in parts or as a whole to valves of other types.

The invention aims to secure a cock in which all wearing and operating parts including the valve seat, could be bodily removed from the casing without removing the cock. To this end the seat, the valve and the valve operating means are mounted in a single carrying member and the carrier member is removably seated in the casing. The advantages of this arrangement should be at once apparent, for upon disarrangement or wearing out of any of the parts, they may be most readily renewed, without the troublesome operation of removing the self-closing cock from the fixture to which it is attached. Particularly in connection with lavatories this is an important advantage since it is many times inconvenient to move the cock from its position.

Special structural features have been invented to aid in the making of the parts specified removable, and the parts carried by the removable member are so organized and this member is so shaped that the member and parts in themselves and independent of the casing constitute a self-closing cock, the casing serving primarily as a means of connection of the carrying member to the supply and delivery pipes or outlets.

The invention aims further to increase the operating efficiency of the valve and cheapen its cost of manufacture.

Herein are inaugurated special structural and combination features to further these ends. Chief among them may be mentioned

the provision of a pressure operating piston controlled by an auxiliary or pilot valve for 55 operating the main valve, and the location of the main valve on the pressure side of the cock in which position it closes with the pressure, the pressure aiding in the closing of it. There is also formed the operating 60 piston chamber of lesser bore at that portion thereof in which the piston rests when in normal position than that portion of the chamber containing the piston when in the open position, in order that corrosion of the 65 walls in advance of the piston may not interfere with the operation of the valve. In the accomplishment of this invention it is applied to a number of specific embodiments, and in the accompanying drawings, 70 is shown one of these embodiments.

Of the drawings:—Figure 1 is a central section of the self-closing cock, and Fig. 2 is a central section of the removable carrying member and the parts carried by it, 75 showing the parts in the open instead of the closed position which is shown in Fig. 1. Fig. 3 is a section taken on the line 3—3 of Fig. 1.

Referring to these drawings, 10 is the 80 valve casing which is of the usual type, having a shank portion 11, a spout 12, a diaphragm or partition 13, normally associated with the valve seat, and a part 14 having an opening through which the valve disk and 85 its operating parts are usually inserted. Usually the valve disk and its operating parts are associated directly with the part 14 of the valve casing. But instead of this usual arrangement, the valve disk and its 90 operating parts are arranged in a carrying member 15 which fits within the member 14. Usually also the valve seat is carried by the partition member 13, but this valve seat is mounted upon the lower end of the carrying 95 member 15, so that the seat as well as the valve, and all wearing and operating parts may be removed at once by the removal of the carrying member 15.

As shown the carrying member is cylindrical in shape, and fits snugly within the part 14 of the casing, and its lower end is seated on the partition 13 above a central opening 16 which is usually the valve opening. A water-tight joint is formed between 105 the end of the carrying member and the par-

tion 13 by packing 17 or by any other suitable means. The carrying member 15 is hollow and at its lower end is provided with the conical seat 18, which seat it is to be noted is in this embodiment smaller than the internal diameter of the member, and the inner edge of the valve seat defines a valve opening. An opening 19 in the walls of the carrying member above the valve seat permits free flow of water from one side of the partition 13 to the other as long as the valve opening is not closed by the valve.

Above the valve seat the carrying member is bored out internally to form a piston chamber 20. A piston 21 is mounted in this chamber, and is provided with a reduced portion 22 projecting through the valve opening, and carrying on its lower end on the pressure side of the cock a main valve 23 for co-operation with the valve seat 18. It is to be noted that the valve 23 is of less area than the piston 21. Above the piston, but below the top of the carrying member is a diaphragm 24. An operating stem 25 passes centrally through the diaphragm and through the carrying member and through the piston 21. The area of the cross section of this valve stem within the piston is made smaller than the opening in the piston through which it passes, as shown in Fig. 3 which is a section taken on line 3—3 of Fig. 1. A second seat 26 is formed upon the main valve surrounding this opening, and a pilot valve 27 carried on the lower end of the stem controls the flow of fluid through this opening to the space below the diaphragm 24 on upper side of the piston. The valves are held normally closed by a spring 28 between the diaphragm 24 and the enlargement or abutment 29 on the stem.

When it is desired to open the valve, the stem is pressed downwardly, and the parts are so arranged, (in this instance by positioning the abutment 30 on the stem so that it is spaced away from the piston 21 in closed position of the pilot valve 27), that the pilot valve opens first upon the downward movement of the stem. Fluid is thereby admitted to the top side of the piston and the piston is forced downwardly by the pressure of the fluid, thus accomplishing, or aiding in the accomplishing of the opening of the valve 23, whereupon fluid flows through the valve opening and around the reduced portion of the stem, and through the opening 19 at the delivery end of the cock. When it is desired that the valve shall be closed, the pressure on the stem is released, whereupon the stem is raised by the spring 28, the valve 27 closed, thus applying spring pressure to the main valve to close it, and at the same time removing the fluid pressure from the top of the piston. Thereupon the pressure of the fluid on the lower side of the piston, and upon the lower end of the main valve 23 car-

ries the main valve to its seat, the fluid from the upper side of the piston escaping between the diaphragm and the stem, the opening in the diaphragm being made large enough for that purpose, and finding its way through passage 31 in the walls of the carrying member 15, and duct 32 through the outlet of the cock.

In order to prevent sticking of the main valve due to corrosion of the carrying member in the piston chamber below the piston in its normal position, the bore of the piston chamber is enlarged below the normal position of the piston. This is clearly seen in Fig. 1. It should also now be apparent that this invention produces an easily operated and most efficient valve. Owing to the operation of the valve through fluid pressure, a minimum pressure of the hand on the operating stem is required, and moreover the stem need be made only so heavy as to withstand its minimum pressure. Structurally the parts are all simple and easily manufactured, most of the work connected with its manufacture being machine work which can be most rapidly done by very rapid machines. And owing to the location of the valve seat, the valve and the valve operating parts in the carrying member the entire group of these parts may be removed at once, and any repairs or rearrangement made which is necessary. Normally the carrying member is held to its seat on the partition 13 by a gland 33. A projection 34 from the carrying member prevents its being turned angularly, and insures its being retained in its position in which it is seated properly on the partition 13. The lower part of the carrying member which carries the valve seat 18 is made separate from the main body in order that the piston 21 may be readily inserted and removed.

What is claimed is:

In a self-closing faucet, the combination with a casing having an attaching shank, an outlet spout, an outstanding hollow body portion intermediate the ends of the casing, an apertured diaphragm in the casing at the inner end of the hollow body portion, and a cap detachably and adjustably mounted on the outer end of the body portion, of a carrying member slidably engaging in the body portion and resting upon the diaphragm and held in position by the cap, said carrying member having a valve seat at its lower end and an opening in one side above the valve seat, the member further having a partition intermediate its ends and a second opening in said side above the partition, the inner diameter of the wall of the lower portion of the carrying member being greater adjacent the valve seat than adjacent said partition, a piston snugly fitting in the lower portion of the carrying member beneath the partition and having a reduced extension projecting

through the lower end of the member and the diaphragm of the casing and having a second valve seat on its lower end, a valve carried on the reduced extension and normally engaging said first named valve seat, an operating stem located centrally in the member and extending through the partition and the diaphragm and through the piston, said stem having a shoulder midway of its ends for engagement with the piston, a valve on the lower end of the stem for engagement with the second valve seat, and a spring about the stem bearing against the

partition and against a second shoulder on the valve stem.

In testimony whereof we have hereunto set our hands in the presence of two subscribing witnesses.
